CALCULATING MACHINE

Edwin F. Britten, Jr., Short Hills, N. J., assignor
to Monroe Calculating Machine Company,
Orange, N. J., a corporation of Delaware

Application March 20, 1936, Serial No. 69,832

3 Claims. (Cl. 235—63)

The invention relates to calculating machines, and more particularly to improved means for shifting the register carriage of such a machine.

The invention consists in the novel construction and combination of parts, as set forth in the appended claims.

In the accompanying drawing illustrating the invention:

Fig. 1 is a right side elevation of a carriage shifting worm and rack, with associated parts.

Fig. 2 is a rear elevation of the same, two reversely threaded worms being shown.

The invention is shown as applied to carriage shifting means of the type disclosed in the U. S. patent to Austin A. Overbury, No. 1,964,478, entitled "Calculating machine", and issued on June 26, 1934. Such means comprise two reversely threaded worms, for shifting the register carriage to the right or to the left, together with means for alternatively connecting one or the other worm with a source of power, the worms being mounted in the base of the machine, and cooperating with the rack fixed to the register carriage. The carriage is also capable of being shifted by direct manual movement from one position to another.

According to the present disclosure, a register carriage, movable transversely along a supporting rod 471, is provided with a transverse rail 472, having lugs supporting a rod 473. The shifting rack is composed of tooth sections 479, independently pivoted on the rod 473, and spaced apart by suitable washers. Springs 474 hold the tooth sections 479 normally in contact with the bar 472, so that collectively they form a rack intersecting the paths of movement of reversely threaded worms 477, 478. These worms are loosely mounted on a shaft 476, and are adapted to be clutched to said shaft by means of cyclic clutches 480, 481 of well known design. Shaft 476 is connected in well known manner with the driving motor of the machine, and the clutching of the respective worm to the shaft is effected by releasing movements of a lever 489 or 490. Worm 477 when clutched to shaft 476 will receive clockwise movement as viewed in Fig. 1, and by contact of the worm with a tooth 479 will move the register carriage one step toward the right. If more than one rotation is given to the worm, the carriage will be moved one or more additional steps to the right, by action of the worm on successive teeth 479 of the rack. Worm 478 is adapted for rotation in the same direction as worm 477, and the action will be similar, except that the carriage will be shifted toward

the left. Springs 474 are of sufficient strength to prevent pivotal displacement of the teeth 479 because of their edgewise contact with the worm.

The threads of the worms 477, 478 do not extend 360 degrees around their hubs, a slot 475 being left between the two ends of the thread through which the rack teeth 479 may pass freely, when the worm is in its normal unclutched position. Because of the slots in the worm threads, the register carriage may be moved transversely by hand, into any desired position, and it therefore happens occasionally that an operator may laterally displace the carriage and fail to bring it into its proper aligned position. In this case one of the teeth 479 will lie in front of the leading edge of the thread of the shifting worm, so that, where a rigid, one-piece rack is employed, the motor will be violently stopped because of the interference of the rack with the worm. According to the present invention however a tooth 479 located in front of the leading edge of a worm 477 will yield pivotally when said worm is started, until the thread of the worm comes to the space between the teeth, at which time the worm will engage the edge of the next tooth 479 and will move the carriage into its correct aligned position. It will be noted that the tooth 479 which effects this partial shifting of the carriage lies in the path of movement of the worm throughout the operation, and that the tooth 479 which had been displaced by the thread of the worm may return freely to its normal position as soon as it is released, since there is no further pressure of the worm tending to hold it away from the rail 472. Pivoted, one-piece racks have heretofore been employed in carriage shifting mechanisms, but in case of pivotal displacement of such a rack by the worm the automatic completion of the shifting movement is dependent upon a rapid dropping of the rack into normal position when the tooth space registers with the thread, this movement also being likely to encounter frictional resistance against the edge of the rack tooth. It may be further noted that the worms 477, 478, obtaining their opposite shifting effect on the carriage through the opposite threading of the worms, rather than through opposite direction of rotation, both worms will act similarly upon the pivoted teeth 479.

I claim:

1. In a calculating machine provided with a transversely shiftable register carriage, carriage shifting means including a worm and a sectional rack engaged by said worm, said rack compris-

50

55

ing spaced, normally aligned coaxially pivoted tooth sections, each of a length slightly less than the pitch of the worm.

2. In a calculating machine provided with a transversely shiftable register carriage, carriage shifting means including a worm, a sectional rack engaged by said worm and comprising spaced, coaxially pivoted tooth sections, each of a length slightly less than the pitch of the worm, springs 10 engaging said sections, and a rail adapted to hold the sections, against the tension of their springs, in alignment to form a rack intersecting the path of movement of the worm.

3. In a calculating machine provided with a

transversely shiftable register carriage, carriage shifting means including a drive shaft, two reversely threaded worms provided each with a releasable connection with said drive shaft, a sectional rack engageable by either worm and comprising spaced, coaxially pivoted tooth sections, each of a length slightly less than the pitch of said worms, springs engaging said sections, and a rail adapted to hold the sections, against the tension of their springs, in alignment to form 10 a rack intersecting the paths of movement of said worms.

EDWIN F. BRITTON, JR.
